UNITED STATES PATENT OFFICE.

ALBERT S. HOWARD, OF PROVIDENCE, RHODE ISLAND, ASSIGNOR TO SMITH WEBBING COMPANY, OF PAWTUCKET, RHODE ISLAND, A CORPORATION OF RHODE ISLAND.

HOLDER FOR WEBBING.

1,076,635.

Specification of Letters Patent. Patented Oct. 21, 1913.

Application filed September 25, 1912. Serial No. 722,396.

To all whom it may concern:

Be it known that I, ALBERT S. HOWARD, a citizen of the United States, and resident of Providence, in the county of Providence and State of Rhode Island, have invented certain new and useful Improvements in Holders for Webbing, of which the following is a specification.

The object of the present invention is to

10 provide a container for rolled fabrics, particularly those in the nature of elastic webbing, tape, ribbon, or any fabric or webbing which is comparatively narrow.

15 The object is to provide a box in which such fabric can be contained and from which it may be drawn as needed, having means for rewinding the fabric when a length greater than is needed has been drawn from the box.

20 A further object has been to provide a simple and inexpensive means for mounting a roll of fabric in a box or container and at the same time to furnish means for rotating the roll for the purpose of winding, as above indicated.

25 In the accompanying drawings wherein I have shown the preferred embodiment of my invention, Figure 1 is a perspective view of the entire container. Fig. 2 is a cross section on line 2—2 of Fig. 1. Fig. 3 is a view similar to Fig. 2 showing a somewhat different arrangement.

The same reference characters indicate the same parts in all the figures.

30 In the drawings the container or box is represented by *a*. This container is conveniently and preferably a pasteboard box of suitable dimensions to contain a roll of webbing, having an opening at one of its sides, or at two opposite sides, if desired, and having a cover *b* to close the open side. As shown in the drawings, the container being of pasteboard construction, the cover is integrally connected with one end wall of 35 the box on a crease *c*, and has a flap *d* to tuck inside the opposite end wall. There are also flaps *e* and *f* on intermediate side walls arranged to underlie the cover when closed. The roll of webbing can be slipped 40 into the open side of the box and inclosed by closing the cover.

As appears from Fig. 2 the webbing *h* is prepared in the form of a roll wound upon a reel or center *i*, which is preferably a tube of pasteboard or other inexpensive material, but may be otherwise constructed. An essential feature of the reel or center, however, is that it shall have a cavity in one end or in both ends. The tubular form is, of course, open from end to end, and this central opening is, for the purpose of the present invention, the equivalent of a cavity extending inwardly from the end of the center. In one of the end walls, as *k*, of the box there is an opening located approximately in the center of the wall and of a size approximating that of the cavity in the reel or center *i*. It is also approximately circular in outline. Owing to its location, it lies in registry with the cavity of the reel center when the roll of webbing is properly placed in the box. *l* represents a thimble or hub having sides so shaped and proportioned as to pass through the opening in the box wall and enter the cavity in the center *i*, 55 when the roll is thus placed in the box. It also has a lip or flange *m* adapted to overlie the outer side of the box wall and cover the edges of the opening therein, giving a finished appearance. The thimble also may 60 have an end wall *l'* crossing the cavity of the center, although this is not an absolutely essential feature of the invention and merely enhances the appearance of the article. The hub or thimble may be described as having 65 an edge or lip overlying the end wall of the box around the opening therein, and having a centrally offset portion passing through such opening into the cavity of the center *i*. The sides of such offset portion, which are 70 in effect the sides of the thimble, fit easily within the center *i*, and the center may thereby be easily inserted and removed. At approximately diametrically opposite points 75 in the sides of the thimble are holes through which pass the ends *o* of a locking device or bail *p*, such bail being preferably of wire and the ends *o* being sufficiently thin to penetrate to some extent the material of the center after passing through the holes of 80 the thimble. Thus the bail connects the thimble to the center, preventing the thimble 85

from dropping out. The bail also serves as a means for rotating the roll to wind the webbing thereon. Consequently it is so formed that it may project outwardly from 5 the thimble as indicated in Fig. 3, and when placed so as thus to project, it may be grasped and turned as a handle. It may, however, be thrown back out of the way, since it is so proportioned between its ends 10 that it may be placed in the offset part of the thimble within the side walls thereof, as indicated in Figs. 1 and 2. The end of the webbing is carried through a slot *q* in one of the sides of the box, as indicated in Fig. 15 1, so that even though the cover of the box be closed, the webbing may be drawn out so that whatever lengths may be needed can be cut off.

It will be seen that a roll of webbing can 20 be easily placed in the box and inclosed therein; that when thus placed it may be secured in such a position as to permit rotating by external application of force, by insertion of the thimble *l* and snapping the 25 bail *p* in place. As the thimble is preferably of sheet metal, the lip *m* adds no appreciable amount to the total thickness of the box, and when the bail is turned back, as shown in Figs. 1 and 2, there is nothing 30 projecting from the side of the box. Hence boxes can be stacked one upon another and when so stacked they rest evenly on each other and form a straight pile.

It is intended that the thickness of the box 35 from one end to the other shall be approximately equal to the width of the webbing as shown in Fig. 3, so that the roll of webbing will be guided by the ends of the box and the turns of the webbing will not slip off 40 from the roll. It may not be practicable, however, to have boxes to fit all sizes of webbing, and so in order to accommodate webbing much narrower than the available box, I provide an attachment shown in Figs. 45 1 and 2. This consists of a guard plate *r* of pasteboard or other similar material adapted to fit easily in the box and having a central hole whereby it may slip over one end of the center or tube *z*. The webbing 50 being rolled about the other end of the tube is confined between the plate *r* and the front wall *k* of the box. Fillers or springs *s* are interposed between the back wall *t* of the box and the plate *r*. These fillers or 55 springs may be made in any desired way and of any suitable material. A convenient and inexpensive way is to make them of a piece of cardboard bent double, but not so far bent as to break and to have its elasticity destroyed. The arrangement where 60 the webbing is approximately equal in width to the interior of the box is shown in Fig. 3.

I claim:

1. A holder for webbing comprising a box

or case, one of the sides of which has an 65 opening approximately in the center thereof, a roll of webbing contained within said box and including a reel center having a recess 70 in one end located in substantial registry with said side opening of the box, a thimble 75 or hub having a rim lying on the outer side of the box and a central portion offset through the side opening into the recess of said reel center, and means detachably securing said thimble to said center. 75

2. A holder for webbing comprising a box or case, one of the sides of which has an opening approximately in the center thereof, a roll of webbing contained within said box and including a tube on which the webbing 80 is rolled, said roll being removable from the box, and when in place having one end of the tube in registry with the side opening 85 of the box, a thimble lying in said tube end and projecting therefrom through said opening and having a lip overlying the box wall, and a spring bail having pintle ends passing through diametrically opposite openings of the thimble into engagement with the tube, serving as a means to secure the thimble 90 detachably to the tube and as a means to rotate the same.

3. A holder for webbing comprising in combination a box, a roll of webbing contained within said box, a reel center upon 95 which said webbing is rolled having a recess in its end, a member contained in said recess, extending through the adjacent wall of the box and having a part overlying such wall, and means for detachably connecting said 100 member to the center.

4. A holder for webbing comprising in combination a box, a roll of webbing contained in said box, a tube on which the webbing is rolled, a hub having tubular walls 105 with holes in them passing through an opening in the wall of the box and into the end of the tube, and a locking device having ends detachably passing through such holes in said tubular walls into engagement with the 110 sides of the tube.

5. A holder for webbing comprising in combination a box having walls, one of which is provided with an opening, a roll of webbing contained in said box, a tube on 115 which the webbing is rolled, a hub having tubular walls with holes in them passing through the opening in the wall of the box and into the end of the tube, and a locking device having ends detachably passing through such holes in said tubular walls into engagement with the sides of the tube, said locking device having a bowed central part pivotally mounted by means of its ends and adapted to be swung into the space surrounded by 120 said tubular walls and into a position wherein it projects from the box wall.

6. The combination of a box having end

walls, a roll of webbing contained in said box, the webbing being of less width than the distance between said end walls, a central member on which said webbing is wound,
5 a plate mounted on one end of said central member, and means between said plate and an adjacent end wall of the box for pressing the plate toward the webbing, whereby

the latter is confined between the plate and the opposite end wall. 10

In testimony whereof I have affixed my signature, in presence of two witnesses.

ALBERT S. HOWARD.
